Specification for Design.

Patented Jan. 23, 1912.

Application filed November 7, 1911. Serial No. 659,059. Term of patent 14 years.

To all whom it may concern:

Be it known that I, JOHN E. MILLER, a resident of Washington, in the county of Washington and State of Pennsylvania, have invented a new and original Design for Globes or Shades, of which the following is a full, clear, and exact description, reference being had to the accompanying drawing, forming part of this specification.

The figure is a side view of a globe embodying my design.

I claim:

The ornamental design for a globe or shade as shown.

In testimony whereof, I have hereunto set my hand.

JOHN E. MILLER.
